UNITED STATES PATENT OFFICE.

HARRY B. GOLDMAN, OF PITTSBURGH, PENNSYLVANIA, ASSIGNOR OF ONE-HALF TO MARSHALL BROTHERS CO., OF PITTSBURGH, PENNSYLVANIA, A CORPORATION OF PENNSYLVANIA.

ELEVATOR-CONTROLLING APPARATUS.

Application filed May 26, 1923. Serial No. 641,726.

To all whom it may concern:

Be it known that I, HARRY B. GOLDMAN, a citizen of the United States, residing at Pittsburgh, in the county of Allegheny and 5 State of Pennsylvania, have invented certain new and useful Improvements in Elevator-Controlling Apparatus, of which the following is a specification.

My invention relates broadly to elevator 10 systems, and more particularly to an apparatus for bringing the elevator to a position of rest with its platform level with a floor adjacent the elevator hatchway.

One of the objects of my invention is to 15 provide an apparatus which may be secured to an elevator and electrically connected with the elevator controller circuits for insuring the stopping of the elevator level with a floor.

20 A further object of the invention is to provide a construction of leveling device for elevators whereby mechanical switches are automatically controlled by movement of the elevator in the hatchway within a leveling 25 zone in proximity to a floor level.

Another object of the invention is to provide a leveling device for elevators which is always automatically operative when the 30 elevator is retarding its acceleration and tending to come to rest at a selected floor level.

Another object of the invention is to provide a leveling device which may be rendered mechanically inoperative when the 35 elevator is traveling up or down the hatchway at speeds which would not be selected when the operator of the elevator desired to bring the car to a position of rest.

Another object of the invention is to provide 40 a construction of leveling device with independent automatic leveling switches arranged to close sets of contacts to electrically control the elevator controller circuits independent of the operator of the car within 45 periods when the car is in a leveling zone in proximity of a floor level.

Another object of the invention is to provide 50 an arrangement of switch contacts which may be substantially insulated from each other to preclude any confusion of the up and down circuits which are controlled by the leveling device.

Other and further objects of the invention will be understood from the following specification by reference to the accompanying drawings, in which:

Figure 1 is a side elevation of an elevator operating in a hatchway adjacent a series of floor levels; Fig. 2 is a front view of the elevator of Fig. 1 showing the relation of the leveling device of my present invention with adjustable cams on the side of the elevator hatchway; Fig. 3 is a cross sectional view showing the up and down adjustable cams which are positioned in proximity of each floor level throughout the vertical height of the hatchway; Fig. 4 is a sectional view taken through my leveling device showing the arrangement of the operating mechanism with parts broken away to more clearly illustrate the operation of the "up" leveling switch; Fig. 5 is a fragmentary view taken on line 5—5 of Fig. 4; Fig. 6 is a plan view of my leveling device with the casing broken away to show the interior arrangement of parts; Fig. 7 is a side elevation of my leveling device showing the arrangement of the up and down rollers and the up and down adjustable cams on the side of the hatchway; Fig. 8 is a sectional view showing the arrangement of the down leveling switch; Fig. 9 is a cross sectional view taken through line 9—9 of Fig. 4; Fig. 10 is a sectional view of my leveling device taken on line 10—10 of Fig. 4; and 85 Figs. 11, 12 and 13 are detailed front and side elevations and cross sectional views of the switch contacts employed in the up and down leveling switches of my leveling apparatus.

My invention will be more clearly understood by reference to my copending application, Serial Number 641,727, filed May 26th, 1923, in which I have described the electrical circuits to which my leveling apparatus is connected.

Referring to Fig. 1 of the drawings, the elevator 1 is illustrated operating up and down the elevator hatchway 2 by means of cable or other mechanism 3 passing floor levels A, B, C, and D. The elevator controller by which the operator controls the movement of the car is indicated at 4. Angle iron 5 is positioned along the vertical

height of the hatchway and secured thereto by bolt 5^a (Fig. 3). This angle iron carries cams 6 and 7 adjacent each floor level adjustable within limits by means of screws 5^b and 7^a operating in slots 6^b and 7^b in cams 6 and 7 respectively. My leveling apparatus is contained in cabinet 8 suitably secured to the elevator 1 by angular bracket 12.

In Fig. 4 a sectional view has been taken 10 through the switch box 15 containing the "up" switch along line 4—4 of Fig. 9. The cabinet 14 containing the leveling apparatus is shown in section. A pair of switch boxes 15 and 16 containing the up switch and the 15 down switch respectively are provided. See Fig. 10. These boxes are journaled upon an axis 17 solidly supported in bracket 12. Angle member 18 forms the journal for switch box 15 about axis 17, and angle member 19 20 forms the journal for switch box 16 about the axis 17. The boxes 15 and 16 are spaced apart by sleeve 20 which also forms a support 21 for axis 17. A weight 22 is secured to the outer corners of the boxes 15 and 16 25 so that normally the switch boxes assume the full line position represented in Fig. 4 but which may be moved to the dotted line position 23 by mechanism to be hereinafter described.

30 The up roller 10 is journaled upon an arm 24 secured to a crank 25 journaled at 26 in switch box 15 with an extended crank arm 27. The crank arm 27 carries a contact 28 comprising a cylindrical sleeve well insulated from the crank arm. When the up roller 10 strikes the up cam 7, this contact 28 is moved between the contracts 29 and 30 to the dotted line position 31. This movement is resisted by spring 32' which 35 normally holds the contact 28 away from the leaf spring contacts 29 and 30. The details 40 of these up and down switches are shown more clearly in Figs. 11, 12 and 13 wherein the leaf springs 29 and 30 are maintained under tension of springs 31 and 32 respectively secured in supports 33 and 34 respectively by means of screws 35 and 36. These 45 screws form terminal posts 37 and 38 from which conductors 39 and 40 lead to the elevator controller circuits. The bracket members 33 and 34 are insulated from each other by insulation member 41 which is here shown secured to the wall of the switch box 15. It is, of course, understood that in the 50 down switch, the member 41 is secured to the wall of switch box 16. The details of the switches are the same for both the up and down switches with the exception that the down switch shown more clearly in Fig. 55 8 is oppositely positioned with reference to the up switch.

The down roller 9 which is arranged to contact with the down cam 6 is journaled on member 42 carried in crank arm 43 which is in turn journaled at 44 and carries a crank

arm 45 within switch box 16. A contact 46 is positioned at the end of the crank arm 45 adapted to be forced between the leaf spring contacts 47 and 48 in dotted line position 49 against the action of spring 50. 70

The leads from the switch terminals are passed through the walls of the switch boxes and secured to terminal posts on insulated block 52 to which exterior electrical connections may be conveniently made with 75 the circuits of the elevator system.

When an elevator equipped with my leveling apparatus is operating at high speed, it is not desired to have the rollers 9 and 10 contact with the cams 6 and 7. To avoid 80 this I provide a leveling magnet 53 supported upon a panel 54 and arranged to attract an armature 55 pivoted at 56. The armature carries an extended arm 57 having a contact 58. When the leveling magnet 53 85 is energized the contact 58 enters between leaf springs 59 and 60 in dotted line position 61, closing an electric circuit controlling the elevator at a speed greater than slow speed. When the magnet 53 is de-energized 90 this circuit is open assuring a slow speed interlock, at which time it is necessary that the leveling switches are out in full line position ready to strike the up and down cams. The connections from leaf springs 95 59 and 60 are made with terminals on the insulated terminal block 52 from which exterior connections may be readily made. The armature 55 is connected through a link 62 with switch boxes 15 and 16. The connection 100 with the upper portions of boxes 15 and 16 is made by means of angular journal brackets 64 and 65 secured respectively to boxes 15 and 16 through which axis member 66 is passed which also passes through journal 105 67 on the end of link 62.

In the operation of my leveling apparatus the cams 6 and 7 are adjusted at each floor level so that when the car platform is exactly level with the landing, the rollers 9 110 and 10 are between the cam faces, thereby allowing both the switch contacts 28 and 46 to be outside of the leaf springs 29 and 30 on the up switch, and leaf springs 47 and 48 on the down switch, as represented in full 115 lines. When the elevator controller 4 has been brought to "off" position as the car nears a landing, the elevator becomes under the control of these leveling switches and will not come to rest until the rollers 9 and 120 10 seek a position between the cams 6 and 7. Should the car move up or down from the landing, due to a load being placed on the elevator or from any other position, either roller 9 or 10 will strike either cam 6 125 or 7. If the car moves down roller 10 rests on cam 7, thereby closing contacts 29 and 30 bringing the car up until it is again level, and the rollers 9 and 10 are between the 130 cams 6 and 7.

When the car is moved by the manual operation of controller 4 the leveling magnet 53 is energized as the controller 4 passes over contacts placing the car in intermediate or high speed, thereby attracting armature 55, drawing back the leveling switches into the dotted line position 23. In this position of intermediate and high speed the elevator travels up and down the hatchway with the 5 rollers 9 and 10 missing the cams 6 and 7. When the elevator controller 4 is moved to low speed position, when it is desired to bring the elevator to rest, the magnet 53 is de-energized and the rollers 9 and 10 drop 10 out upon the faces of the up and down cams which are sufficiently extended along the elevator hatchway. When the elevator controller is brought to "off" position the car will be brought to rest when the rollers 9 and 10 seek a position between the cams.

While I have described my invention in a certain particular embodiment, it is to be understood that I intend no limitations other than those imposed by the scope of 25 the appended claims.

What I claim is:

1. A leveling device for elevators comprising in combination an elevator hatchway, pairs of adjustable cams mounted on 30 said hatchway, a pair of pivotally mounted switch boxes, levers independently pivoted adjacent each of said switch boxes, a roller carried on one end of each lever, and an electrical contact carried on the other end 35 of each lever, a pair of independent contacts in each of said switch boxes whereby the electrical contact on said switch arms is forced between said switch contacts when said rollers abut against said cams.

2. A leveling device for elevators comprising in combination an elevator hatchway, a pair of vertically spaced adjustable cams adjacent each floor along said hatchway, a pair of independent switches carried 45 by said elevator, means connected to each switch adapted to contact with a separate cam of each of said pairs of cams for independently closing said switches, and means for withdrawing said contacting means out 50 of alignment with said cams.

3. In a leveling device for elevators, the combination of an elevator hatchway, pairs of cams on said hatchway, a pair of independently pivoted switches carried by said 55 elevator, each separately cooperating with each of said cams, independent switch boxes containing contact members for said switches, a common journal for each of said boxes, an armature, a connecting rod between said said armature and said switch boxes, and an electromagnet arranged to attract 60 said armature whereby said switches are withdrawn out of alignment of said cams and an electrical circuit simultaneously closed.

4. A leveling device for elevators comprising in combination a pivoted mounting, a plurality of switches carried by said pivoted mounting, separate switch arms mounted to turn in said mounting and means secured 70 to said switch arms whereby said switches may be separately closed, and electrical means for simultaneously moving said switch arms to inoperative position.

5. A leveling device for elevators comprising in combination an elevator hatchway, a pair of adjustable cams adjacent each floor along said hatchway, a pair of independent switches carried by said elevator, means adapted to contact with said cams for closing said switches, a weight normally tending to hold said means in alignment with said cams, and additional means for withdrawing said first mentioned means out 80 of alignment with said cams.

6. In a leveling device for elevators, the combination of an elevator hatchway, pairs of cams on said hatchway, a pair of independently pivoted switches carried by said elevator, each separately cooperating with each of said cams, independent switch boxes containing contact members for said switches, a common journal for each of said boxes, a weight normally tending to hold 90 said switches in alignment with said cams, an armature, a connecting rod between said armature and said switch boxes, and an electromagnet arranged to attract said armature whereby said switches are withdrawn out 95 of alignment of said cams and an electrical circuit simultaneously closed.

7. A leveling device for elevators comprising in combination an elevator hatchway, pairs of adjustable cams mounted on said hatchway, a pair of pivotally mounted switch boxes, levers independently pivoted adjacent each of said switch boxes, a roller carried on one end of each lever, and an electrical contact carried on the other end 100 of each lever, a pair of independent contacts in each of said switch boxes whereby the electrical contact on said switch arms completes a circuit across said switch contacts when said rollers abut against said 105 cams.

8. In a leveling device for elevators, a hatchway, an elevator operative therein, a pivoted mounting carried by said elevator, a plurality of switches carried by said pivoted mounting, separate switch arms mounted to turn in said mounting, a plurality of cams on said hatchway, and means secured to said switch arms whereby said switches may be separately closed by abutment with 110 said cams, means for limiting the movement of said mounting in the direction of said cams, and means for moving said mounting in a direction away from said cams.

9. In a leveling device for elevators, the combination with an elevator hatchway of 115 120 125 130

adjustable cams adjacent each floor level along said hatchway, leveling apparatus comprising pairs of independent contacts, independent spring pressed switches arranged to close said contacts against the action of said springs by abutment with said cams, a single means for both supporting

said switches and limiting their movement in the direction of said cams, and means for withdrawing said switches out of alignment of said cams. 10

In testimony whereof I affix my signature.

HARRY B. GOLDMAN.
